(57) **CLAIM**

The ornamental design for a golf cart seat cover, as shown and described.

DESCRIPTION

FIG. 1 is a front view of a golf cart seat cover, showing my new design;

FIG. 2 is a rear view thereof;

FIG. 3 is a bottom plan view thereof;

FIG. 4 is a top plan view thereof;

FIG. 5 is a left side view thereof;

FIG. 6 is a right side view thereof;

FIG. 7 is a front, bottom and left side perspective view thereof; and,

FIG. 8 is a use state view thereof.

The broken lines shown in the drawings illustrate portions of the golf cart seat cover that form no part of the claimed design.

The broken lines found on the claimed surfaces along the perimeter trim are stitching that forms a part of the claimed design.
